UNITED STATES PATENT OFFICE

111,318

DESIGN FOR A PANEL FOR A MEMORIAL STRUCTURE

Selma O. Colbe, Chicago, Ill.

Application February 15, 1938, Serial No. 75,155

Term of patent 7 years

To all whom it may concern:

Be it known that I, Selma O. Colbe, a citizen of the United States and residing at 4031 North Menard Avenue, Chicago, in the county of Cook and State of Illinois, have invented a new, original, and ornamental Design for a Panel for a Memorial Structure, of which the following is a specification, reference being had to the accompanying drawing, forming part thereof.

Fig. 1 is a front elevation of a panel for a memorial structure embodying my new design, and

Fig. 2 is an end view of the panel taken on line 2—2 of Fig. 1.

I claim:

The ornamental design for a panel for a memorial structure, as shown.

SELMA O. COLBE.
